ADJUSTING MECHANISM ADAPTED FOR LINE CONTROL

Filed Jan. 29, 1921

2 Sheets-Sheet 2

Fig. 3.

Fig.

A detailed line drawing of a lock's internal mechanism. It features a central pin (25) with a circular top and a tapered bottom. A shank (24) is inserted through a hole in the pin. Below the pin, a keyway (23) is shown with a dashed outline, indicating the path of a key. The entire assembly is set against a background with concentric circles, suggesting a circular housing or cross-section.

UNITED STATES PATENT OFFICE.

LUDWIG HOLLAND-LETZ, OF OAK PARK, ILLINOIS.

ADJUSTING MECHANISM ADAPTED FOR LINE CONTROL.

Application filed January 29, 1921. Serial No. 440,835.

To all whom it may concern:

Be it known that I, LUDWIG HOLLAND-LETZ, a citizen of the United States, and a resident of Oak Park, in the county of Cook 5 and State of Illinois, have invented certain new and useful Improvements in Adjusting Mechanism Adapted for Line Control, of which the following is a full, clear, and exact specification.

10 My invention is concerned with a line control mechanism, which I have shown as applied to the throttle valve of the carburetor of a gas engine for a tractor, but which might be applied to the throttle of 15 a steam engine instead of a gas engine, or to control the position of the spark, and which is adapted for use wherever it may be necessary to shift an element back and forth step by step by pulling on a line.

20 To illustrate my invention, I annex hereto, two sheets of drawings in which the same reference characters are used to designate identical parts in all the figures of which—

Fig. 1 is a somewhat diagrammatic view 25 of a tractor driven by an explosion engine having my invention applied thereto;

Fig. 2 is an enlarged view of the operating connections as seen in side elevation;

Fig. 3 is a top plan view of the same 30 partly in section on the line 3—3 of Fig. 2;

Fig. 4 is a view in section on the line 4—4 of Fig. 2;

Fig. 5 is a fragmentary view of the mechanism shown in Fig. 1, but in a different 35 position of the parts;

Fig. 6 is a side elevation as seen from the right of Fig. 4 of the end of the bracket on which the operating mechanism is mounted;

40 Fig. 7 is a fragmentary view of the actuating lever detached, seen from the left-hand side of Fig. 4; and

Fig. 8 is a diagrammatic view showing 45 how my invention is applied to gas engine tractors which are provided with automatic speed regulators.

In carrying out my invention as applied to an ordinary gas engine tractor 9 illustrated in Fig. 1, the carburetor 10 is secured 50 to the under side of the manifold 11 attached to the engine 12 in the customary manner. The arm 13 controlling the throttle valve 14 (indicated in dotted lines) has pivotally connected to its outer end a link 15, the other end of which is pivotally secured

to the element to be reciprocated, which preferably takes the form of a ratchet sector 16 (see Figs. 2 to 5) which preferably has on the outside thereof the plurality of threaded apertures 17 therein in the same 60 diametrical line but at different distance from the center so that the eccentric pin 18 upon which the link 15 is pivoted may be screwed at any necessary distance from the center to adapt it to carburetors having 65 arms 13 of different lengths, and yet have it operate properly without changing it otherwise. A bracket 19 is provided with two holes 20 by which it may be bolted at any desired place upon the tractor frame, and 70 it has mounted in a boss 21 thereon a bearing shaft 22 on the outer end of which is journaled the ratchet sector 16, while the operating lever 23 is fulcrumed on its inner end. A rope 24 has one end fastened in the 75 loop 25 of the lever, and extends rearward to any trailer (indicated by its tongue 26) where the driver may be located, and if by repeatedly pulling the free end of the rope the driver can rotate the ratchet sector 80 16 backward or forward step by step, it will be obvious that he can control the speed of the tractor through its throttle valve irrespective of the angular position of the trailer to the tractor or of his position on 85 the trailer. In practice, to facilitate its manipulation from any angle, I reverse the position of the mechanism, as shown in dotted lines in Fig. 1, and run the line 24 over a pivotal sheave 24^a. While I have 90 omitted illustrating them for the sake of simplicity, it will be understood that the tractor will be provided also with some form of line control for starting and stopping and reversing, and with another line 95 control for shifting the gears, such, for instance, as are shown in my applications No. 403,735, filed August 16, 1920, and No. 483,091, filed July 7, 1921, respectively.

The apertures 17 are preferably formed in a rib 27 projecting from the outer face of the sector 16, and one end of said rib co-operating with a stop lug 28 projecting from the outer side of the bracket 19 when the throttle valve is closed, toward which position the sector 16 is always urged by the helically coiled torsion spring 29 surrounding the boss 21 on the bracket 19 and the hub 30 of the sector 16 and having its ends engaging the lugs 31 and 32 on the ad-

100

105

110

jacent faces of the sector and bracket, respectively. Another helically coiled torsion spring 33 surrounding the boss 34 at the fulcrum of the lever 23 and having its ends 5 engaging the lugs 35 and 36 on the lever 23 and the bracket 19, respectively, always urges the lever 23 clockwise to its normal position indicated in dotted lines in Fig. 2, where the lever is stopped by its adjacent 10 side engaging a lug 37 projecting from the rear of the bracket 19. The lever 23 has a web 38 projecting from its front with a down turned portion 39, and the pivot pin 40 (see Figs. 3 and 4) of a pair of pawls 15 41 and 42 passes through said portion 39 and the body of the lever. The pawls 41 and 42 co-operate with the teeth 43 of the ratchet sector 16, the pawl 41 being hooked to advance the sector 16 one tooth each time 20 it is swung from the dotted to the full line position of Fig. 2, while it and the pawl 42 also have an escapement action, to be described later, through their co-operation with the lifting flange 44 forming a part of 25 the bracket 19 as seen in Figs 2 to 6, and having two cam surfaces 45 and 46 with which the ends of the pawls 42 and 41 respectively, co-operate in the manner to be described. A helically coiled torsion spring 30 47 surrounds the boss 48 of the pawl 41 and its ends engage the lug 49 (Fig. 3) on the pawl 42 and the body of the pawl 41, respectively, to press the operating ends of the pawls into engagement with the ratchet 35 teeth 43 when they are not held out by the action of the flange 44, the pawls 41 and 42 having the extensions 50 and 51, respectively, projecting rearwardly into the vertical plane of the flange 44 and having their 40 under surfaces symmetrical with the teeth engaging ends of their pawls. A hooked detent pawl 52 is fulcrumed on a pin 53 carried by a lug 54 on the bracket 19 and has its inwardly projecting end 55 normally 45 held in engagement with the teeth 43 by the helically coiled torsion spring 56 surrounding a boss 57 on the lug 54 and having its ends engaging the lug 54 and an arm 58 projecting upwardly from the fulcrum of the pawl 52. When the lever 23 is pulled 50 to its furthest position from normal as seen in full lines in Fig. 5, a lug 59 projecting therefrom engages the end of the arm 58, rocking the end 55 of the detent pawl 55 out of engagement with the teeth 43, leaving the sector to be controlled by the escapement action of the pawls 41 and 42. A stiff helically coiled torsion spring 60 surrounds the annular boss 61 projecting rearwardly 60 from the end of the bracket 19 and has one end secured to said bracket while the other end 62 projects up into the path of a lug 63 projecting forwardly from the lever 23 so as to be engaged thereby at the intermediate position of the lever shown in full lines

in Fig. 2. The end 62 normally engages the lug 63^a projecting toward the lever 23 from the bracket 19, and is held thereby in the path of the lug 63. The operation of the connections thus described is as follows: 70

If the throttle valve is entirely closed, the parts are in the position shown in dotted lines in Fig. 2, and to open the throttle, the driver pulls the rope 24 toward him until the lug 63 engages the end of the spring 62 which offers an additional resistance to the pull of the lever indicating to the driver that the limit of that movement to open the throttle has been reached. During this movement, the dog 41 advances the ratchet one tooth and it is caught in the advanced position by the dog 52. If it is to be opened wider, the swing of the lever 23 to the half way position by pulling the rope 24 is repeated as often as is necessary, advancing the ratchet sector a tooth at a time until the desired speed of the engine is obtained. When the throttle is to be closed, the rope is pulled as before to the half way position, advancing the ratchet sector 16 another 80 tooth, but instead of stopping when the additional resistance of the spring 62 is encountered, the pull is continued until the parts reach the full line position shown in 85 Fig. 5. This results in the following action of the parts: The dog 41 moves forward carrying with it the ratchet sector 16 before its nose 50 rides up on the cam surface 46 and is disengaged from the tooth before the ratchet sector has been advanced far enough 90 for the dog 52 to catch in another tooth. At the same time that the nose 50 is riding up on the cam surface 46, the nose 51 of the pawl 42 rides down the cam surface 45, and rests either on top of the tooth directly beneath it, or preferably slightly past the point of the tooth, so that when the lug 59 strikes the arm 58 and lifts the nose 53 of the dog 52 out of engagement with the ratchet teeth, thus allowing the spring 29 100 to throw the ratchet sector back, the said sector can swing back only until the tooth in advance of the nose 51 of the pawl 42 engages it and stops the backward movement of the ratchet sector before it has moved the full length of a tooth. The operator now allows the arm 23 to swing back under the influence of the spring 33 to the point where the lug 63 disengages itself 110 from the end 62 of the spring 60, or any distance beyond that, except that it must not be allowed to move all the way back so that the nose 50 of the pawl 41 catches a new tooth. During this backward movement, the nose 51 of the pawl 42 rides up on the surface 45 and disengages itself from the tooth, but before this happens, the lug 59 on the lever 23 has moved back far enough to allow the spring 56 to throw the detent 52 into operation again so that the ratchet segment 115 120 125 130 135

can only move backward the fraction of a tooth necessary to bring the adjacent tooth into engagement with the nose 55 on the pawl 52. This action is substantially that of an escapement, and the result of the complete forward pull of the lever 23 from the dotted line position of Fig. 2 to the full line position of Fig. 5 and its return to the full line position of Fig. 2 is to first advance the ratchet sector 16 one tooth and then allow it to spring back one tooth. The operator then pulls the lever 23 forward from the middle position to the full line position of Fig. 5 and allows it to swing back to the middle position, and the result of this movement is to allow the ratchet sector 16 to move back one tooth, and each time this reciprocation is repeated, it allows the sector to move back a tooth until the extension 27 strikes the lug 28 and stops the mechanism with the throttle completely closed, if that much of a movement in that direction is desired. Beyond the last tooth 43 of the sector 16, I form a surface 43^a over which the nose 50 of the pawl 41 reciprocates idly if it be attempted by repeated movement of the lever 23 to swing the sector 16 beyond the wide open position of the throttle.

Where the invention is applied to a tractor having an automatic stop governor, which is shown diagrammatically in Fig. 8, instead of the link 15 extending from the crank pin 18 to the arm 13, a divided link made of the two parts 15^a and 15^b is employed, and the adjacent ends have hooks engaging loops in the ends of the helically coiled contractile spring 15^c. Connected to the arm 13 of the throttle valve is a link 64 which is connected at the other end to the lever 65 fulcrumed at 66 on the casing 67 for the governor, which is shown as consisting of an extension 68 of the engine shaft having mounted thereon the pair of centrifugal governor weights 69 which have the arms 70 engaging a disk 71 sliding on the reduced end of the shaft 68 and separated by the ball-bearing 72 from the flange 73 on the inner end of the stud 74 mounted to rotate on said reduced inner end and having its outer end engaging the lever 65 so that when the engine speeds up, the governor weights 69 are thrown out and the stud 74 is pushed out, swinging the lever 65 to draw the arm 13 in the proper direction to close the throttle and thus bring the speed of the engine back to the desired limit. By the use of the arm 23, the tension of the spring 15^c can be increased or diminished as may be necessary to affect the desired speed for which the automatic speed governor is set.

While I have shown and described my invention as embodied in the form which I at present consider best adapted to carry out its purposes, it will be understood that it is capable of modifications, and that I do not

desire to be limited in the interpretation of the following claims, except as may be necessitated by the state of the prior art.

What I claim as new and desire to secure by Letters Patent of the United States is:

1. In an apparatus of the class described, the combination with an element to be reciprocated, of a reciprocating actuating element, a flexible element connected to the actuating element to move the latter in one direction, means to return the actuating element automatically when moved from its normal position by said flexible element, and connections between said element to be reciprocated and said actuating element which by pulling the flexible element in a certain way moves the element to be reciprocated in one direction and by pulling it in another way moves the element to be reciprocated in the other direction.

2. In an apparatus of the class described, the combination with an element to be reciprocated, of a reciprocating actuating element, a flexible element connected to the actuating element to move the latter in one direction, a spring to return the actuating element automatically when moved from its normal position by said flexible element, and connections between said element to be reciprocated and said actuating element which by pulling the flexible element in a certain way moves the element to be reciprocated in one direction and by pulling it in another way moves the element to be reciprocated in the other direction.

3. In an apparatus of the class described, the combination with an element to be reciprocated, of a reciprocating actuating element, a flexible element connected to the actuating element to move the latter in one direction, means to return the actuating element automatically when moved from its normal position by said flexible element, a spring tending to return the element to be reciprocated when advanced from its normal position, detent mechanism to hold it advanced, and connections between said element to be reciprocated and said actuating element by which a short pull on the flexible element advances the element to be reciprocated a short distance where it is held by the detent, and a longer pull releases the detent and allows the spring to move it back.

4. In an apparatus of the class described, the combination with an element to be reciprocated, of ratchet teeth associated with said element, a spring tending to move it backward, a detent co-operating with the teeth to hold it advanced, a reciprocating actuating element, a flexible element connected to the actuating element to move the latter in one direction, means to return the actuating element automatically when moved from its normal position by said flexible element, and connections between the teeth of said ele-

- ment to be reciprocated and said actuating element whereby a short pull of the flexible element advances the element to be reciprocated one tooth where it is caught by the 5 detent, and a further pull beyond the position to which it is brought by the short pull releases the detent and allows the element to be reciprocated to move back the distance of one tooth.
- 10 5. In an apparatus of the class described, the combination with an element to be reciprocated, of a reciprocating actuating element, a flexible element connected to the actuating element to move the latter in one 15 direction, means to return the actuating element automatically when moved from its normal position by said flexible element, connections between said element to be reciprocated and said actuating element which by 20 pulling the flexible element in a certain way moves the element to be reciprocated in one direction and by pulling it in another way moves the element to be reciprocated in the other direction, and a yielding stop associated 25 with said connections to indicate by its resistance that the limit of the pull to move the element to be reciprocated in one direction has been reached.
- 30 6. In an apparatus of the class described, the combination with an element to be reciprocated, of a reciprocating actuating element, a flexible element connected to the actuating element to move the latter in one direction, means to return the actuating element automatically when moved from its 35 normal position by said flexible element, connections between said element to be reciprocated and said actuating element which by 40 pulling the flexible element in a certain way moves the element to be reciprocated in one direction and by pulling it in another way moves the element to be reciprocated in the other direction, and a strong spring normally not energized serving as a yielding 45 stop.
7. In an apparatus of the class described, the combination with an element to be reciprocated, of a reciprocating actuating element, a flexible element connected to the actuating element to move the latter in one direction, means to return the actuating element automatically when moved from its normal position by said flexible element, ratchet teeth 50 associated with the element to be reciprocated, a pair of pawls carried by the actuating element co-operating with the teeth, a lifting flange co-operating alternately with said pawls to move them out of engagement with the teeth, a detent pawl co-operating with 55 the teeth and a spring tending to move the element to be reciprocated backward, said elements being so designed that a short pull of the flexible element advances the element to be reciprocated one tooth and holds it 60 without either of the two pawls being af- fected by the lifting flange, while the longer pull causes one of said pawls to be lifted by the flange and the other to be released from the flange, and the detent pawl to be lifted out of the teeth by the movement of the actuating element so that the total result of the longer movement is to first advance the element to be reciprocated one tooth, then return it one tooth, leaving the parts in position whereby the repetition of the final 70 portion of the longer movement will permit the element to be reciprocated to move back step by step.
8. In an apparatus of the class described, the combination with a ratchet sector, of a 75 spring tending to move it backwardly, an actuating lever fulcrumed concentrically with the sector, a pair of spring pressed pawls carried by the lever and adapted to engage the teeth of the sector, a lifting flange adapted to hold said pawls alternately out of engagement with the teeth, a 80 spring tending to return the actuating lever and a spring pressed detent pawl engaging the teeth, the parts being so proportioned, and designed so that when the actuating lever is moved forward from its initial position a unit distance one of the pawls advances the ratchet sector a tooth, where it is held by the detent pawl, while when it is moved farther the actuating lever engages against the detent pawl and the lifting flange permits one of the pawls carried by the lever to alternate in its action with the detent pawl 85 to form an escapement whereby the ratchet sector can be moved backward a tooth at a time by reciprocating the actuating lever back and forth beyond the unit distance.
9. In an apparatus of the class described, the combination with a ratchet sector, of a 90 spring tending to move it backwardly, an actuating lever fulcrumed concentrically with the sector, a pair of spring pressed pawls carried by the lever and adapted to engage the teeth of the sector, a lifting flange adapted to hold said pawls alternately out of engagement with the teeth, a 95 spring tending to return the actuating lever and a spring pressed detent pawl engaging the teeth, the parts being so proportioned and designed so that when the actuating lever is moved forward from its initial position a unit distance one of the pawls advances the ratchet sector a tooth, where it is held by the detent pawl, while when it is moved farther the actuating lever engages against the detent pawl and the lifting flange permits one of the pawls carried by the lever to alternate in its action with the detent pawl 100 to form an escapement whereby the ratchet sector can be moved backward a tooth at a time by reciprocating the actuating lever back and forth beyond the unit distance.
10. In an apparatus of the class described, the combination with a ratchet sector, of a 105 spring tending to move it backwardly, an actuating lever fulcrumed concentrically with the sector, a pair of spring pressed pawls carried by the lever and adapted to engage the teeth of the sector, a lifting flange adapted to hold said pawls alternately out of engagement with the teeth, a 110 spring tending to return the actuating lever and a spring pressed detent pawl engaging the teeth, the parts being so proportioned and designed so that when the actuating lever is moved forward from its initial position a unit distance one of the pawls advances the ratchet sector a tooth, where it is held by the detent pawl, while when it is moved farther the actuating lever engages against the detent pawl and the lifting flange permits one of the pawls carried by the lever to alternate in its action with the detent pawl 115 to form an escapement whereby the ratchet sector can be moved backward a tooth at a time by reciprocating the actuating lever back and forth beyond the unit distance.
11. In an apparatus of the class described, the combination with a ratchet sector, of a 120 spring tending to move it backwardly, an actuating lever fulcrumed concentrically with the sector, a pair of spring pressed pawls carried by the lever and adapted to engage the teeth of the sector, a lifting flange adapted to hold said pawls alternately out of engagement with the teeth, a 125 spring tending to return the actuating lever and a spring pressed detent pawl engaging the teeth, the parts being so proportioned and designed so that when the actuating lever is moved forward from its initial position a unit distance one of the pawls advances the ratchet sector a tooth, where it is held by the detent pawl, while when it is moved farther the actuating lever engages against the detent pawl and the lifting flange permits one of the pawls carried by the lever to alternate in its action with the detent pawl 130 to form an escapement whereby the ratchet sector can be moved backward a tooth at a time by reciprocating the actuating lever back and forth beyond the unit distance.

resistance which it offers when the limit of the unit distance has been reached in the forward movement of the actuating lever.

10. In an apparatus of the class described, 5 the combination with a ratchet sector, of a spring tending to move it backwardly; an actuating lever fulcrumed concentrically with the sector, a pair of spring pressed pawls carried by the lever and adapted to engage the teeth of the sector; a lifting flange adapted to hold said pawls alternately out of engagement with the teeth, a spring tending to return the actuating lever, a spring pressed detent pawl engaging the 15 teeth, the parts being so proportioned and designed so that when the actuating lever is moved forward from its initial position a unit distance one of the pawls advances the ratchet sector a tooth, where it is held by the detent pawl, while when it is moved farther the actuating lever engages against the detent pawl and the lifting flange permits one of the pawls carried by the lever to alternate in its action with the detent 20 pawl to form an escapement whereby the ratchet sector can be moved backward a tooth at a time by reciprocating the actuating lever back and forth beyond the unit distance, and a strong spring normally not 25 under tension coiled about the axis of the actuating lever and having an end extending into the path thereof when the limit of the unit distance has been reached.

11. In a tractor, the combination with an engine, of a throttle valve controlling the speed thereof, a reciprocating element connected to said valve, a flexible member, and connections between said flexible member and reciprocating element whereby by repeatedly pulling the flexible member the throttle valve may be opened and closed to any desired extent.

12. In a tractor, the combination with an engine, of a throttle valve controlling the speed thereof, a reciprocating element connected to said valve, a flexible member, and connections between said flexible member and reciprocating element whereby by pulling the flexible member the reciprocating element may be moved step by step in either direction so as to open and close the throttle valve to any desired extent.

13. In a tractor, the combination with an engine, of a throttle valve controlling the speed thereof, an element to be reciprocated connected to said valve, a reciprocating actuating element, a flexible element connected to the actuating element to move the latter in one direction, means to return the actuating element automatically when moved from its normal position by said flexible element, and connections between said element to be reciprocated and said actuating element which by pulling the flexible element in a certain way moves the element to be recipro-

cated in one direction and by pulling it in another way moves the element to be reciprocated in the other direction.

14. In a tractor, the combination with an engine, of a throttle valve controlling the speed thereof, an element to be reciprocated connected to said valve, a reciprocating actuating element, a flexible element connected to the actuating element to move the latter in one direction, means to return the actuating element automatically when it is moved from its normal position by said flexible element, a spring tending to return the element to be reciprocated when advanced from its normal position, a detent mechanism to hold it advanced, and connections between said element to be reciprocated and said actuating element by which a short pull on the flexible element advances the element to be reciprocated a short distance where it is held by the detent, and a longer pull releases the detent and allows the spring to move it back.

15. In a tractor, the combination with an engine, of a throttle valve controlling the speed thereof, an element to be reciprocated connected to the throttle valve, ratchet teeth associated with said element, a spring tending to move it backward, a detent cooperating with the teeth to hold it advanced, a reciprocating actuating element, a flexible element connected to the actuating element to move the latter in one direction, means to return the actuating element automatically when moved from its normal position by said flexible element, and connections between the teeth of said element to be reciprocated and said actuating element whereby a short pull of the flexible element advances the element to be reciprocated one tooth where it is caught by the detent, and a further pull beyond the position to which it is brought by the short pull releases the detent and allows the element to be reciprocated to move back the distance of one tooth.

16. In a tractor, the combination with an engine, of a throttle valve controlling the speed thereof, an element to be reciprocated connected to said valve, a reciprocating actuating element, a flexible element connected to the actuating element to move the latter in one direction, means to return the actuating element automatically when moved from its normal position by said flexible element, ratchet teeth associated with the element to be reciprocated, a pair of pawls carried by the actuating element cooperating with the teeth, a lifting flange cooperating alternately with said pawls to move them out of engagement with the teeth, a detent pawl cooperating with the teeth and a spring tending to move the element to be reciprocated backward, said element being so designed that a short pull of the flexible element advances the element to be recipro-

- cated one tooth and holds it without either of the two pawls being affected by the lifting flange, while a longer pull causes one of said pawls to be lifted by the flange and 5 the other to be released from the flange and the detent pawl to be lifted out of the teeth by the movement of the actuating element so that the total result of the longer movement is to first advance the element to be 10 reciprocated one tooth, then return it one tooth, leaving the parts in position whereby the repetition of the final portion of the longer movement will permit the element to be reciprocated to move back step by step.
- 15 17. In an apparatus of the class described, the combination with an element to be reciprocated, of a reciprocating actuating element, a flexible element connected to the actuating element to move the latter in one 20 direction, means to return the actuating ele-

ment automatically when moved from its normal position by said flexible element, connections between said element to be reciprocated and said actuating element whereby pulling the flexible element in a certain way moves the element to be reciprocated in one direction and by pulling it another way moves the element to be reciprocated in the other direction, and a signaling device associated with said connections to indicate 25 that the limit of the pull to move the element to be reciprocated in one direction has been reached.

In witness wherof, I have hereunto set my hand and affixed my seal, this 17th day of 35 January, A. D. 1921.

LUDWIG HOLLAND-LETZ. [L. s.]

Witness:

JOHN HOWARD McELROY.
